UNITED STATES PATENT OFFICE.

FRED B. COREY, OF EDGEWOOD, PENNSYLVANIA.

LIGHTNING-ARRESTER.

1,161,195.

Specification of Letters Patent. Patented Nov. 23, 1915.

Application filed January 23, 1915. Serial No. 3,962.

To all whom it may concern:

Be it known that I, FRED B. COREY, a citizen of the United States, residing at Edgewood, in the county of Allegheny and State 5 of Pennsylvania, have invented certain new and useful Improvements in Lightning-Arresters, of which the following is a specification.

My invention relates to lightning arresters and especially to that class of lightning arresters in which spark-gaps are provided between the circuit to be protected and the ground to which the static charge is to be diverted.

10 The object of my invention is to provide such a lightning arrester that will give ample protection to the apparatus connected with it and that will not itself be damaged by the passage to ground of a heavy induced 20 discharge through it.

My invention consists in the combination with multiple spark-gaps in a lightning arrester, or a group of lightning arresters connected to the same circuit, of coils, consisting of a few turns of wire, in series with the said spark-gaps and arranged in pairs, each pair being in mutually inductive relation and differentially connected so as to offer a non-inductive path to the discharge 30 only when this discharge is equally divided between the said multiple spark-gaps, thus tending automatically to equalize the discharge through all of the spark-gaps and prevent serious burning at any one of them.

35 In the drawings that illustrate my invention, Figure 1 is a top view of a lightning arrester having two spark-gaps and embodying my improvements. Fig. 2 is a side view, partially in section, and Fig. 3 is a 40 transverse section through the center of the same arrester. Fig. 4 is a diagram showing the arrangement of the differentially arranged coils when the number of spark-gaps is greater than two.

45 Referring to Figs. 1, 2 and 3, A represents a hollow block of porcelain or other insulating material on and in which the other parts are mounted. B is a terminal screw with a thin square head, held in place 50 in the base A by the nut N¹. On this terminal screw is mounted the disk C, preferably made of some non-fusible, conducting material such as carbon. This disk is held in place by the nut N⁶ and above this nut are 55 two washers W¹ and W² and the terminal nuts T¹ and T². On either side of the ter-

60 minal screw B are similarly mounted screws D¹ and D² held in place by the nuts N² and N³ respectively and carrying the disks E¹ and E² which are preferably made of brass or other metal and have their outer cylindrical surfaces knurled to form a large number of points rather than a smooth surface. These disks are held in place by the nuts N⁴, N⁵, N⁶ and N¹⁰. On either side of these 65 screws D¹ and D², are mounted the terminal screws F¹ and F² which are held in place by the nuts N⁴ and N⁵ above which are the washers W³, W⁴, W⁵ and W⁶ and the terminal nuts T³, T⁴, T⁵ and T⁶. These screws 70 F¹ and F² are joined by the copper wire K, making them electrically as one, the two screws being provided merely for convenience in connecting the arrester into the circuit to be protected. Inclosed within the 75 base A is an insulating tube P, upon which two pieces of wire H and J, preferably of copper, are wound, forming two concentric helices. The helical conductor H serves to connect the screw D¹ to the conductor K and the terminals F¹ and F² attached thereto. In like manner the helical conductor J serves to connect the screw D² to the conductor K and terminals F¹ and F². After the parts are mounted in place, the interior 80 space S is filled with melted sealing wax or other insulating compound of an adhesive nature and the cover plate L is inserted and is held in place by the solidified sealing compound.

90 The operation of this lightning arrester is as follows: The terminal post B is connected to ground. The static charge, entering the arrester through one of the terminal screws F¹ or F², will flow to the metal disks E¹ and E² and will jump to ground through the disk C and the terminal screw B. The charge will tend to jump the shorter of the two spark-gaps G¹ or G². The discharge across the spark-gap is alternating in 95 character and of high frequency. The helical conductor H or J therefore introduces a reactance in series with the spark-gap. When, however, the discharge passes equally across the two spark-gaps in multiple, the 100 helical conductors H and J become non-inductive, as the flux that would be set up within one helix is neutralized by the flow of electrical energy in the other helix. Since, therefore, the impedance of the path of the 105 discharge is least when it is equally divided across the two spark-gaps, it will automati- 110

cally so divide, as it will thus find the path of least impedance to ground.

Referring now to Fig. 4, the connections are shown by which the discharge is equalized between a number of lightning arrester spark-gaps. Y and Z are two conductors, one of which is connected to the line to be protected and the other is connected to ground. V¹, V², V³, V⁴, V⁵, V⁶, V⁷ and V⁸ are spark-gaps, one side of each of which is connected to the conductor Y and the other side of each is connected to conductor Z through the differentially arranged coils X¹, X², X³, X⁴, X⁵, X⁶ and X⁷. The coil X¹ is formed by conductors a¹ and b¹ united at c¹. The remaining coils are similarly formed of conductors similarly designated. The amount of discharge passing across the spark-gaps V¹ and V² and through the conductors a¹ and b¹ is equalized by the coil X¹ and the amount passing through the remaining pairs of spark-gaps V³ and V⁴, V⁵ and V⁶ and V⁷ and V⁸ are equalized in the same way by the coils X², X³ and X⁴. In like manner the discharge passing through coil X¹ and conductor a⁵ and that passing through coil X² and conductor b⁵ is equalized by the coil X⁵, and that passing through conductors a⁶ and b⁶ is equalized by the coil X⁶. Thus, also, by the action of the coil X⁷, the discharge through the conductor a⁷ is equalized with that through conductor b⁷. Thus, by the combined action of seven differentially arranged coils the discharge across the eight spark-gaps is equalized so that one-eighth of the discharge passes each spark-gap. It will be seen that in accordance with my invention, two spark-gaps may be equalized with one coil, four spark-gaps with three coils, eight spark-gaps with seven coils or sixteen spark-gaps with fifteen coils.

I do not desire to limit myself to the exact construction and arrangement of parts here shown, but aim in the appended claims

to cover all modifications which are within 45 the scope of my invention.

What I claim as new and desire to secure by Letters Patent of the United States is—

1. In a lightning arrester, the combination of multiple spark-gaps and reactance coils 50 in series with the said spark-gaps, said coils comprising each a pair of concentric windings reversely wound whereby their reactance is neutralized when the current flowing in each of the said windings is equal. 55

2. In a lightning arrester, the combination of multiple spark-gaps and reactance coils in series with the said spark-gaps, said coils comprising each a pair of coils reversely wound on a single core whereby their reactance is neutralized when the current flowing in each of the coils is equal. 60

3. In a lightning arrester, the combination of two multiple spark-gaps and a coil comprising a pair of concentric windings each 65 in series with one of the said spark-gaps, the said windings being reversely wound whereby their reactance is neutralized when the current flowing in each of the windings is equal. 70

4. In a lightning arrester, an insulating base, two spark-gaps mounted thereon, one electrode of each of the said spark-gaps being connected to one terminal of the said lightning arrester, the opposite electrodes 75 of the said spark-gaps being connected to the other terminal of the lightning arrester through concentric reactance coils reversely wound whereby their reactance is neutralized when the current flowing in each of the 80 said coils is equal.

In witness whereof, I have hereunto set my hand this 22 day of January, 1915.

FRED B. COREY.
